ALBERT G. BUZBY, OF PHILADELPHIA, PENNSYLVANIA.

Letters Patent No. 78,422, dated June 2, 1868.

IMPROVED RAILROAD-RAIL.

The Schedule referred to in these Letters Patent and making part of the same.

TO ALL WHOM IT MAY CONCERN:

Be it known that I, ALBERT G. BUZBY, of Philadelphia, county of Philadelphia, State of Pennsylvania, have invented a Clip for Railroad-Rails; and I do hereby declare the following to be a full, clear, and exact description of the same.

My invention consists of a clip composed of a thin plate of steel, bent and applied to a rail or rails, substantially as described hereafter, so as to cover the gaps between adjacent rails, and prevent the injurious shocks and jars which occur when the car-wheels pass these gaps. My improved clip is also applicable as an effective patch for wounded rails.

In order to enable others to make and apply my invention, I will now proceed to describe its construction and operation, reference being had to the accompanying drawing, which forms a part of this specification, and in which—

Figure 1 is a side view of my improved clip for railroad-rails.

Figure 2, a transverse section on the line 1-2, fig. 1.

Figure 3, a sectional view of the upper portion of one of the rails.

Similar letters refer to similar parts throughout the several views.

The rails to which my improved clip is applied are in the present instance of the ordinary form, having the usual tread *a*, web *b*, and lower flanges *d* and *d'*.

A and *A'*, fig. 1, represent the ends of two adjacent rails, the open space between which is represented by the dotted lines *x x*.

B is the clip, one-half of which is arranged to embrace the end of one rail, *A*, the other half embracing the end of the adjacent rail, *A'*, in the manner illustrated in fig. 2.

The clip consists of a thin plate of steel, bent in the middle, so as to be adapted to the treads of the rails, curved inwards at the sides, so as to approach but not be in contact with the web *b*, and one end of the plate is bent beneath one of the flanges, *d*, and the other beneath the opposite flange, *d'*, as shown at *y y*, fig. 1, or the ends of the plate which forms the clip may be bent beneath a plate, *f*, overlapping both rails.

The treads of both rails are recessed, as shown at *t*, fig. 3, to receive the clip, so that the upper surface of the latter may be level with the upper surface of the main portion of the rail.

Two bolts, *m m*, pass, one through the web *b* of one rail, and one through that of the adjacent rail, both bolts passing through the clip and through bars *D D*, one on one side and the other on the opposite side of the said clip, so that on tightening the nuts of the said bolts, the clip will be contracted and drawn tight over the recessed portions of the ends of the two rails.

The holes in the clip through which the bolts pass are such that the rails can expand and contract to a limited extent, independently of each other.

There is always more or less of an open space between the rails of railroads, and it is well known that owing to this open space the ends of the rails are more rapidly worn than other portions, the car-wheels passing across the open spaces causing such shocks and jars as to injuriously affect the iron at these points, at the same time injuring the wheels themselves, while they are the main cause of the wear and tear of both the running-gear and permanent portions of cars and locomotives.

The object of my invention is to so cover the gaps between the rails that these injurious shocks cannot occur, a duty effectually accomplished by the above-described clip, which can be drawn so tightly over the treads of the rails as to become essentially a part of the same.

The utility of my invention is not limited to the joints of rails, as the clip may be applied with advantage to any portion of a rail the tread of which has been unduly worn, the clip serving as a patch for the wounded portion.

I claim as my invention, and desire to secure by Letters Patent—

A clip composed of a thin flexible plate of steel or tough iron, bent and applied to a rail or rails, substantially as and for the purpose herein set forth.

In testimony whereof, I have signed my name to this specification in the presence of two subscribing witnesses.

A. G. BUZBY.
